United States Patent Office

Des. 208,335
Patented Aug. 15, 1967

208,335

MOTION PICTURE CAMERA HOUSING

Lawrence R. Teeple, Jr., San Carlos, and Leonard N. Albrecht, Mill Valley, Calif., assignors to Beckman & Whitley, Inc., San Carlos, Calif., a corporation of Delaware

Filed Sept. 7, 1965, Ser. No. 86,876

Term of patent 14 years

(Cl. D61—1)

FIG. 1 is a left-side elevational view of a motion picture camera housing showing our new design;

FIG. 2 is a right-side elevational view thereof;

FIG. 3 is a top plan view thereof;

FIG. 4 is a bottom plan view thereof;

FIG. 5 is a rear elevational view thereof; and

FIG. 6 is a front elevational view thereof.

We claim:

The ornamental design for a motion picture camera housing, substantially as shown.
